UNITED STATES PATENT OFFICE.

ALFRED HEALD, OF PHILADELPHIA, PENNSYLVANIA, ASSIGNOR TO HUGH McCALLUM, ORLANDO CREASE, ANDREW J. SLOAN, AND WM. McCALLUM, OF SAME PLACE.

DESIGN FOR CARPET-PATTERN.

Specification forming part of Design No. **7,114**, dated January 20, 1874; application filed January 10, 1874.
[Term of Patent 3½ years.]

CASE O.

To all whom it may concern:

Be it known that I, ALFRED HEALD, of the city and county of Philadelphia, State of Pennsylvania, have produced or invented a Design for a Carpet-Pattern, of which the following is a specification:

My design for a carpet-pattern is fully represented by the figure in the accompanying drawing, the remainder being merely a repetition of that which appears.

The principal members of the pattern are the figures A, B, and C, the spaces between which are occupied by a series of scrolls. The central figure A is oblong, and adjoins the corners of two opposite figures, B, the latter being nearly square in outline, and each having a deep ornamented border, *a*, within which is an elaborate central ornament, *b*. Each of

the figures C is composed mainly of four crescent-shaped members, *d*, and of intervening shading, all of which is of a character too clearly shown in the drawing to require minute description.

Irrespective of the colors employed, I claim—

The design for a carpet-pattern composed of figures A, B, and C, and of a ground ornamented by scrolls, as set forth, and illustrated in and by the accompanying drawing.

In testimony whereof, I have signed my name to this specification in the presence of two subscribing witnesses.

ALFRED HEALD.
